G. KLUMPP,
LUBRICATING DEVICE.
APPLICATION FILED FEB. 6, 1919.

Patented Oct. 5, 1920.

UNITED STATES PATENT OFFICE.

GOTTLOB KLUMPP, OF NEW YORK, N. Y.

LUBRICATING DEVICE.

1,354,765.

Specification of Letters Patent.

Patented Oct. 5, 1920.

Application filed February 6, 1919. Serial No. 275,302.

To all whom it may concern:

Be it known that I, GOTTLÖB KLUMPP, a citizen of Germany, having declared my intention of becoming a citizen of the United States, and a resident of the borough of Manhattan, city, county, and State of New York, have invented certain new and useful Improvements in Lubricating Devices, of which the following is a specification.

- 10 My improvements relate to devices of the cup-funnel type used for holding and feeding a semi-fluid lubricant to journal bearings and the like; and the main object is to attain a satisfactory and perfect gravity feed, obviating the need of followers, forcing springs, etc.,—such contrivances being more or less complicated, expensive, and objectionable for various practical reasons. Other objects are, to render visual at all 20 times the presence or absence of an adequate quantity of the lubricant within the container and to effectually secure the parts in closed relationship in a simple manner. Hence, the invention consists in the specific 25 construction and arrangement of parts described and claimed,—distinctive features being my gravity feed stem, the visualizing means, and the securing and closing means, all as hereinafter fully set forth.

30 In the accompanying drawings,

Figure 1, is an elevation of my improved lubricating device;

Fig. 2, is a top view thereof, with the cover removed;

35 Fig. 3, is a sectional elevation taken upon plane of line 3—3, Figs. 1 and 2;

Fig. 4, is a top view of the cup shell alone;

Fig. 5, is a side view of the cup alone, looking in the direction of the arrow α , 40 Fig. 2;

Fig. 6, is an end view of the window cylinder;

Fig. 7, is a side view thereof;

45 Fig. 8, is an elevation of the gravity feed stem;

Figs. 9 and 10, are respectively upper and lower end views thereof;

Fig. 11, is a sectional detail, on a larger scale, of one of the cover snap fastenings, 50 etc.;

Fig. 12, is a similar view showing a modification of the snap fastening;

Fig. 13, is an inside view of the cup cover; and

55 Fig. 14, is a view showing a modification of the cover spring.

The container for the lubricant (not shown) is essentially a funnel shaped cup C, the discharge passage c , from which extends through the threaded nipple c' , by means of which latter the container C, is attached to the cap plate of a journal bearing, or the like, as indicated by dotted lines in Fig. 3.

The upper portion of the container C, is preferably although not necessarily cylindrical in general configuration, and is formed with a plurality of sight apertures c^x , preferably extending all the way to and through the top of the shell of the cup C, so as to form between said sight apertures c^x , sections of side wall c^2 , which are more or less elastic and resilient at their upper portions,—it being understood that the shell of the container C, is metallic.

My preferred form of lubricator has three 75 of these elastic resilient sections c^2 , of side wall, equidistant, and consequently has three equidistant sight apertures c^x , between them, although I do not restrict myself in this respect, except to state that a plurality of 80 both sight apertures c^x , and elastic resilient wall sections c^2 , is desirable. Each elastic resilient wall section c^2 , is formed, near its upper free edge, with an external knob or protuberance c^3 , made preferably by upsetting the metal outward, in a manner well known in the art. The flange k , of the cover K, is formed with coincidental internal recesses or sockets k' , so that these protuberances c^3 , on the elastic resilient wall 90 sections c^2 , of the container C, and these cover sockets k' , for the reception thereof, constitute practically snap fastenings to hold the cover K, in position. I thus attain not only very simple and cheap, but very 95 effective means, for removably attaching the cover K, to the container C.

A little below the lower edge of the sight openings c^x , I form the container C, with an internal annular shoulder c^4 , which constitutes the seat of a transparent lining G, preferably consisting of a cylinder of glass, which fits snugly upon its seat c^4 , and within the casing, the window sills c^5 , overlapping the joint between the lower edge of the cylinder G, and the casing, and hugging the cylinder with sufficient tightness to prevent the exuding of lubricant over said sills c^5 , as will be understood by reference to Fig. 3. In this connection it may be stated that when the cover K, is applied the upper portions of the elastic resilient sections c^2 , also

fit the cylinder G, snugly, but that they otherwise have sufficient play to admit of the snapping of the cover in place with its sockets k' , fitting over the protuberances c^2 , on said elastic resilient wall sections of the container shell.

The cover K, is also formed on its inner side with a flat spring k^2 , which bears peripherally, when the cover K, is positioned 10 on the container C, against the upper edge of the glass cylinder G, as shown more particularly in Figs. 3 and 5, of the accompanying drawings, thus not only holding the glass cylinder G, firmly on its seat c^4 , but 15 also holding taut and firm the snap fastenings c^3 , and k' , and preventing looseness or rattling of the parts involved. It is obvious that the flat spring k^2 , instead of being in the form of a disk with a continuous annular periphery, might with like results be 20 formed with a plurality of radial arms adapted to contact with the upper edge of the cylinder G, as for instance the modification of said spring k^2 , shown in Fig. 14.

F, is a gravity feed stem positioned centrally and loosely or freely within the container C, and extending at its lower extremity through the discharge passage c , thereof so as to rest against a journal to be 25 lubricated, as indicated more particularly in Fig. 2, in which the dotted circle J, represents the cross section of a journal. The feed stem F, is preferably, although not necessarily, made of three wires f , f , f , of equal 30 length, bound together by a wrapping of solder, lead, or alloy f' , and having their upper ends bent over laterally as related to the center of the stem to form equidistant radial arms f^2 , f^2 , f^2 , which space and centralize the upper end of the feed stem within, and as related to, the cylindrical part of 35 the container C. By the use of a plurality of wires f , f , f , in the formation of the feed stem F, I, in a convenient and cheap manner, provide it with a plurality of feed 40 grooves f^3 , f^3 , f^3 , which, by aiding capillary attraction, facilitate the feed by gravity of the lubricant down the lower portion of the stem and through the discharge passage c , 45 of the container C, and to the parts to be lubricated. The wrapping f' , not only unites itself with the wires f , f , f , integrally, but it also performs the function of a weight to hold the feed stem F, down to its 50 work in the relatively thick, semi-fluid lubricant which is introduced into the container C, in which function the feed stem is supplemented by the vibration to which the parts are subjected under ordinary conditions of use, such mechanical vibration also causing more or less rotation of the feed stem on its central vertical axis, so that its lateral arms f^2 , f^2 , f^2 , not only space and centralize the upper part of the feed stem F, as 55 before stated, but also act, to a certain ex-

tent, as agitators to insure the descent of the lubricant within the container.

The structure of feed stem F, above described is simple, cheap and effective, requiring no tooling nor skilled labor; but it is 70 obvious that like results may be attained by a solid stem formed with longitudinal grooves equivalent to those (f^3) formed by and between the wires f , f , f , shown. Also 75 that the feed stem F, may be weighted by other means than the binding wrapper f' .

It is also obvious that the coincidental snap fastenings c^3 , k' , might be reversed as related to each other with like result: that is to say, the protuberance might be on the 80 flange k , of the cover K, and the socket on the elastic resilient side wall c^2 , of the container C, as illustrated in Fig. 12, so that I do not limit myself to either alternative construction of snap fastening.

What I claim as my invention and desire to secure by Letters Patent is,

1. In a lubricating device of the character designated, in combination, a container casing the upper part of which is formed with a plurality of elastic resilient wall sections alternating with sight apertures, a cover fitting over the upper edges of said elastic resilient wall sections; coincidental snap protuberances and sockets engageably formed on said elastic resilient wall sections and cover, and a transparent lining in the said upper part of the container casing, for the purpose described.

2. In a lubricating device of the character designated, in combination, a container casing the cylindrical upper part of which is formed with a plurality of elastic resilient wall sections alternating with sight apertures, a cover fitting over the upper 105 edges of said elastic resilient sections, coincidental snap protuberances and sockets engageably formed on said elastic resilient wall sections and cover, and a cylindrical glass lining in the said upper part of the 110 container casing, for the purpose described.

3. In a lubricating device of the character designated, in combination, a container casing the cylindrical upper part of which is formed with a plurality of elastic resilient wall sections alternating with sight apertures, a cover fitting over the upper edges of said elastic resilient sections, coincidental snap protuberances and sockets 115 engageably formed on said elastic resilient wall sections and cover, a cylindrical glass lining in the said upper part of the container casing, and an annular seat for the lower edge of said glass lining formed for it in the casing, for the purpose described.

4. In a lubricating device of the character designated, in combination, a container casing the cylindrical upper part of which is formed with a plurality of elastic resilient wall sections alternating with sight 120

- apertures, a cover fitting over the upper edges of said elastic resilient sections, coincidental snap protuberances and sockets engageably formed on said elastic resilient wall sections and cover, and a cylindrical glass lining in the said upper part of the container casing, an annular seat for the lower edge of said glass lining formed for it in the casing, and a spring on the inner side of said cover adapted to bear against the upper edge of said cylindrical glass lining and hold it against its said annular seat in the casing, for the purpose described.
5. In a lubricating device of the character designated, in combination with the container formed with the discharge passage at its lower extremity, a free gravity feed stem positioned centrally and loosely within the container and extending through its said discharge passage, and formed with longitudinal grooves in its lower portion, and with three equidistant lateral spacing arms at its upper portion, for the purpose described.
10. In a lubricating device of the character designated, in combination with the container formed with the discharge passage at its lower extremity, a weighted gravity feed stem positioned centrally and loosely within the container and extending through its said discharge passage, said feed stem 30 consisting of a plurality of wires united by a medial weight member, the upper ends of said wires being spread apart radially to form equidistant spacing arms, and the 35 lower portions of said wires being in contact and forming longitudinal feed grooves between them, for the purpose described.
15. In a lubricating device of the character designated, in combination with the container formed with the discharge passage at its lower extremity, a weighted gravity feed stem positioned centrally and loosely within the container and extending through its said discharge passage, said feed stem 40 consisting of three wires bound together by a medial weight member, the upper ends of said wires being bent over laterally to form equidistant spacing arms, and the lower 45 portions of said three wires being in contact and forming longitudinal feed grooves 50 between them, for the purpose described.
20. In a lubricating device of the character designated, in combination with the container formed with the discharge passage at its lower extremity, a weighted gravity feed stem positioned centrally and loosely within the container and extending through its said discharge passage, said feed stem 45 consisting of three wires bound together by a medial weight member, the upper ends of said wires being bent over laterally to form equidistant spacing arms, and the lower 50 portions of said three wires being in contact and forming longitudinal feed grooves between them, for the purpose described.
25. In a lubricating device of the character designated, in combination with the container formed with the discharge passage at its lower extremity, a weighted gravity feed stem positioned centrally and loosely within the container and extending through its said discharge passage, said feed stem 45 consisting of three wires bound together by a medial weight member, the upper ends of said wires being bent over laterally to form equidistant spacing arms, and the lower 50 portions of said three wires being in contact and forming longitudinal feed grooves between them, for the purpose described.

GOTTLÖB KLUMPP.
